UNITED STATES PATENT OFFICE.

DANIEL M. COOPER, OF ROCHESTER, NEW YORK, ASSIGNOR TO AMERICAN LAUNDRY MACHINERY COMPANY, OF CINCINNATI, OHIO, A CORPORATION OF OHIO.

IRONING-MACHINE.

1,209,124.

Specification of Letters Patent. Patented Dec. 19, 1916.

Application filed November 14, 1912. Serial No. 731,264.

To all whom it may concern:

Be it known that I, DANIEL M. COOPER, of Rochester, in the county of Monroe and State of New York, have invented certain new and useful Improvements in Ironing-Machines; and I do hereby declare the following to be a full, clear, and exact description of the same, reference being had to the accompanying drawings, forming a part of this specification, and to the reference-numerals marked thereon.

My invention relates to improvements in ironing machines, with reference particularly to the class of machinery employed for pressing shirt bosoms, and embodying a stationary platen and movable presser, the latter being provided with means for supporting and retaining the garment, and it has for its object to provide a novel arrangement of parts for effectively clamping the neck bands of varying sizes.

Another object of my invention consists in providing a relatively movable bosom board which is so connected to the adjustable elements of the neck band clamp that the neck band of the garment will always maintain the same relative position on the board, the shoulder and neck portions of the shirt being always maintained at the same points of the board.

A still further object of my invention resides in a novel form of clamping mechanism for engaging the lower end of the garment whereby it may be stretched until it is tightly and smoothly held upon the board and in means for locking the clamping device in engagement with the garment until it is ready to be released.

To these and other ends the invention consists in certain improvements and combinations of parts all as will be hereinafter more fully described, the novel features being pointed out in the claims at the end of the specification.

In the drawings: Figure 1 is a longitudinal, sectional view of a portion of an ironing machine having embodied therein a preferred form of my invention; Fig. 2 is a sectional view on the line 2^a—2^a of Fig. 1; Fig. 3 is a view in side elevation of the machine, with parts in section; Fig. 4 is a plan view of the neck band clamping means; Fig. 5 is a plan view of the neck band engaging devices; Fig. 6 is a similar view of the stationary neck band engaging member; Fig. 7

is a view in end elevation of the garment clamping means; Fig. 8 is a side elevation of the same, showing the clamping members in normal or inoperative position; Fig. 9 is a similar view with the clamping members engaged and locked. Fig. 10 is a detail view in side elevation of one of the spring controlled clutches, and Fig. 11 is a sectional view of the same.

Similar reference characters through the several views indicate the same parts.

In the present embodiment of the invention, 1 designates the stationary platen, which is engaged by a vertically movable presser adapted to carry a garment, the presser being supported in bearings 2. The presser embodies a support 3, above which is arranged the garment supporting device or bosom board 4, the latter being slidable upon the support. To this end, the bosom board embodies a base 5, provided with a steam chamber 6, and carrying a toothed rack 7, which is engaged by a gear segment 8 mounted upon the shaft 9, the latter being provided with an operating lever 10 for moving the bosom board longitudinally of the support. In order to hold the board in its adjusted position and also to return it to normal position, the base 5 carries spring actuated rods 11 which are located on opposite sides of the support and are movable within the guides 12. Upon the support 3 are pivotally mounted spring controlled clutches 13 in engagement with the rods 11, and serving to hold the latter in their adjusted position until released by the pawl 14, the latter being formed on a sleeve fixedly mounted on the rock shaft 15, which may be operated by the lever 16 secured thereto.

17 is a neck band engaging member which is stationary relatively to the support and is mounted upon a post 18, the latter being attached as shown in Fig. 1, to the plate 19, secured in any suitable manner to the support, as by means of bolts 22. The base 5 of the bosom board is slidable upon the plate 19, and has a dovetailed joint with the support 3 as shown in Fig. 2.

Arranged upon the stationary neck band engaging member 17 is a pair of guideways 105 23 which are angularly disposed and receive the slides 24, the latter forming parts of the adjustable neck band engaging devices designated at 25. The stationary neck band engaging member is provided with 110

curved flanges 26 adapted to engage the front portions of the neck band while 27 are flanges on the adjustable neck band engaging devices which coöperate with the 5 rear corner portions of the neck band and are movable forwardly and rearwardly to effect close engagement with neck bands of different sizes. For accomplishing this movement, the slides 24 are provided with 10 pins or projections 28 which engage slots 29 in the yoke member 30, the latter being suitably attached to a standard 31 which is secured at its lower end to the flange 32 of the base 5. It will be noted that the bosom 15 board is cut away at 33 to receive the post 18 on which the stationary neck band engaging member is mounted. When the adjustable neck band engaging devices are moved to accommodate a larger or smaller 20 neck band, the bosom board is correspondingly moved, so that the rear edge of the board and the rear edge of the neck band will always be in substantially the same vertical plane as shown in Figs. 4 and 5. 25 This enables a shirt of any size to be pressed, while retaining the neck band always in the same relative position to the yoke and shoulder portions of the garment, thus obtaining a regular and even pressing 30 of any sized shirt, and this effect cannot be secured in a machine where the bosom board is stationary.

34 is a clamp for engagement with the rear edge of the bosom board, which is 35 mounted upon a pivotally arranged arm 35, controlled by a lever 36. The lever 36 is pivotally attached to a rod 37 which is yieldably connected with the arm 35. The lever 36, when rocked on the post 33^a, locks the 40 clamp 34 against the garment, and is adapted to be released at the instant that the bosom board and adjustable neck band engaging devices are returned to their normal position. To this end, the lever 36 carries a 45 tail piece 38 which is arranged in the path of a rod 39, the latter being pivotally connected to an arm 40 carried by the aforementioned lever 16. When the latter is operated to release the bosom board, permitting it to be returned to its normal position 50 through the action of the springs 41, rod 39 engages tail piece 38 of lever 36, rocking it over until the connecting rod 37 passes the dead center or locking position, whereupon 55 the clamp 34 is released by the action of the spring 42.

The garment is clamped at its lower end by means that may be adjusted with relation to the bosom board so as to hold different sized garments, and with varying degrees of tightness, and to this end I provide a carrying device 43 provided with guide rods 44 at opposite sides of the board arranged for movement in guides 45, the latter being suitably secured upon the board

and controlled by springs 46. The carrying device 43 embodies a shaft 47 on which is journaled the upper clamping member 48.

49 designates an operating member for actuating the clamping members, which is 70 fixedly mounted on the shaft 47, and carries an upwardly projecting portion 50 engaging a spring 51 arranged between it and the clamping member 48. The shaft 47 has rigidly secured thereto at its opposite end a 75 sleeve 52 having an arm 53 supporting a spring 51 between it and the corresponding part of the clamping member 48, both of the springs 51 being of the same construction. The lower clamping member is designated at 54, being mounted on the shaft 47 by means of the arms 55 which are provided with downwardly extending ears 56 by which the clamping member is connected to the bosom board through links 57, the latter being in turn secured to a shaft 58, which is mounted in standards 59. The normal position of the clamping member 54 is determined by an adjusting plate 60 which is attached to the clamping member by a set 90 screw 61 operating through a slot 62. The position of the plate 60 is controlled by an adjusting screw 63 having threaded engagement with the arm 64 on an ear 56.

65 is a stop formed upon the clamping 95 member 48 and coöperating with the lug 66 on the operating member 49 to return the clamping member to its normal position shown in Fig. 8.

67 is a pivoted clutch coöperating with 100 the guide rod 44 to hold the same in adjusted position, and said clutch may be released by the lug 68 mounted upon the rock shaft 58, which is controlled in a manner which will presently be described. It will be seen 105 that when the operating member 49 is depressed, the springs 51 are compressed, forcing the upper clamping member into engagement with the lower clamping member. A further movement of the operating member 110 effects a still closer engagement between the clamping members, while at the same time causing them to move together in a downward direction as the guide rods 44 are moved outwardly, until the parts assume the 115 position shown in Fig. 3.

In order to hold the clamping members in operative engagement, locking means are provided embodying a weighted locking device 69, carried by the operating member, 120 and provided with a locking pawl 70 arranged to engage a coöperating recess in the plate 60. This locking means serves to hold the upper clamping member in close engagement with the lower clamping member. 125 Upon releasing the clutch 67, the parts return to substantially the position shown in Fig. 9, at which point the tail piece 71 on the locking device engages a releasing means, preferably in the form of an abutment 72, 130

mounted on the carrying device. This causes the lower end of the locking device to be raised, withdrawing the pawl 70 from its recess, and permitting the upper clamp-
5 ing member to return to its normal position as in Fig. 8.

73 is a rod connected to the rock shaft 58 by a lever 74, and provided at its lower end with the spring 75 which is arranged to be
10 engaged by the extension 76 during the up-
ward movement of the presser. By this means, the clamping devices may be automatically released immediately prior to the engagement of the heated platen with the
15 bosom board on the presser.

I claim as my invention:

1. The combination with a support, of a
bosom board mounted on the support, a car-
rying device movable longitudinally of the
20 support, clamping members arranged on
the carrying device, and adapted to engage

each other, an operating member for actuating the clamping members, a locking device carried by the operating member and operating to hold the clamping members in en-
gagement, and releasing means arranged on the carrying device and adapted to engage
the locking member.

2. The combination with a support, of a
bosom board mounted on the support, a car-
rying device movable longitudinally of the
support, clamping members arranged on the
carrying device, an operating member for
actuating the clamping members and a lock-
ing device arranged on the operating mem-
ber and coöperating with one of the clamp-
ing members for holding them in engage-
ment.

DANIEL M. COOPER.
